Patented Jan. 16, 1968

209,938

MEDICAL LINEAR ACCELERATOR

Street S. Chang, Walnut Creek, Calif., assignor to Applied Radiation Corporation, Walnut Creek, Calif., a corporation of Delaware

Filed Mar. 3, 1967, Ser. No. 6,053

Term of patent 14 years

(Cl. D83—1)

FIG. 1 is a perspective view of a medical linear accelerator showing my new design;

FIGURE 2 is a front elevational view thereof.

FIGURE 3 is a top plan view thereof; and

FIG. 4 is a side elevation thereof.

The dominant features of my design reside in the portions shown in full lines.

I claim:

The ornamental design for a medical linear accelerator, as shown and described.
